UNITED STATES PATENT OFFICE.

ROBERT J. GASKILL, OF FORT WAYNE, INDIANA, ASSIGNOR TO THE GAMEWELL COMPANY, OF NEWTON, MASSACHUSETTS, A CORPORATION OF MASSACHUSETTS.

SIGNAL LAMP.

Application filed November 15, 1924, Serial No. 750,037. Renewed January 12, 1928.

The invention relates to lamps and particularly to electric signal lamps.

It is desirable where signal lamps are in use to so arrange the lamp that its interior may be readily accessible without removing or disturbing the lens. At the same time it is desirable that the lamp may be tightly closed against the elements and dirt.

The object of the invention is to provide a lamp wherein the lens is continuously supported in the lamp frame, yet readily removable therefrom when desirable, the frame having means affording access to the interior of the lens for cleansing it or for renewal or adjustment of the incandescent lamp.

Other objects will appear hereinafter.

The invention consists of a canopy or cap and ring detachably connected together in a novel manner with a cylindrical lens clamped between them, the base ring affording access to the interior thereof and normally closed in novel manner.

The invention is illustrated in the accompanying drawings in which—

Figure 1 is an elevational view of the lamp, partly in section; Fig. 2 a bottom plan view of the canopy; Figs. 3 and 4 detail views of the supports in the canopy for the clamping or tie bolts; Fig. 5 a plan view of the ring; Fig. 6 a central cross-sectional view of the ring; Fig. 7 a detail view of the lock for the closure of the ring and Fig. 8 an elevational view of the canopy illustrating the socket for the incandescent lamp in inverted position.

In the illustrative embodiment of the invention, 1 is the canopy or cap. It is preferably conical in shape and hollow. The peak of the canopy is apertured and internally threaded as at 2 for attachment to a conduit or bracket by which the lamp is supported or suspended. The service wires enter through this aperture and are connected to the usual terminals of an incandescent lamp socket 3.

The socket 3 is formed in two sections, one of which threads into the other, and which clamp between them the offset central apertured portion 4 of a plate 5. Each end of the plate is slotted at 6, the central portion of each slot being enlarged in order that the plate may be passed over the heads of the screws 7 engaged in the canopy 1 and then rotated in either direction to cause one

end of each slot to receive one of the screws. The screws are then tightened and the plate is held firmly in position. As shown in Fig. 1 the offset portion of the plate projects downwardly, thereby enabling a short incandescent lamp to be used and assure its centering with respect to the cylindrical lens 8. When a longer lamp is used the plate is inverted as shown in Fig. 8. Thus two lengths of incandescent lamps may be used and assure that the filament in either case will lie in the center of the bull's eye-section 8^a of the lens. Since the slot in each end of the plate 6 extends upon opposite sides of the central enlarged portion of said slot, the plate may be turned in either direction to engage under the heads of the screws according to whether the offset portion 4 projects upwardly or downwardly, and when so turned the bulb is centered in the vertical axis of the lens.

An annular recess 9 is formed in the lower edge of the canopy for the reception of a gasket 10 preferably formed of rubber, and upon which gasket the upper end of the lens 8 engages.

At selected points on the inner periphery of the canopy 1 are formed the bifurcated lugs 11, the free end of each arm of each lug having an upstanding extension 12. Above each lug the inner wall of the canopy slopes inwardly and upwardly rather sharply. This inclination may be formed in suitable manner, as by the lugs 13. The lug 13 is shorter than the arms of the lug 11 beneath it so as to leave a small space between its outer end and the upper ends of the extensions 12 to permit the bolts 14 to be withdrawn from the lugs 11 or inserted therein when inclined as shown in Fig. 3. The slot in each lug 11 is of such width that the head of the bolt will not pass through it and the squared portion of the bolt adjacent the head thereof prevents rotation of the same in the slot. To withdraw the bolt from the lug 11 it is necessary to incline it and pass the head over the upper ends of the extensions 12 as shown in Fig. 3. When the bolts depend from the lugs 11 they cannot disengage therefrom since their heads are below and relatively close to the inclined lower faces of the lugs 13 and will abut the same if the bolts are elevated. The extensions 12 prevent any lateral disengaging movement of the bolts on the lugs 11. The

lower ends of the bolts are extended through apertures formed in the base 15.

The ring 15 has the annular seats 16 and 17 formed on the upper and lower surfaces 5 of its outer annular portion. A gasket 18 is engaged on the seat 16 and the lower end of the lens 8 engages the gasket when the nuts 19 are drawn up on the bolts 14 to clamp the lens rigidly between the canopy and the 10 ring. There is sufficient play of the bolts in the lugs 11 to permit of the centering of the ring on the lens with the flange 15^a projecting into the lens.

A gasket 20 is engaged on the seat 17 and 15 is normally engaged by the upper edge of an annular flange 21 formed on the cover plate 22, having a downwardly projecting rib or other member 23 on its outer face to facilitate the rotation of the cover in locking 20 and unlocking it to and from the ring.

The lock for the cover comprises a bar 24 normally held on two lugs 25 by the conically coiled springs 26, the upper ends of the springs having engagement with the 25 heads of the screws or posts 27 connected to or projecting upwardly from the lugs. The bar 24 is loose on the screws 27 and the under side of each end of the bar is bevelled or rounded off, the thin edge at one 30 end of the bar being on the opposite side edge of the bar relatively to the thin edge at the opposite end of the bar. A cam is therefore formed at each end of the bar and it is adapted to engage a cam 28 formed on 35 the top side of a lug 29 that projects from the inner peripheral wall of the ring.

When the cover is to be attached to the ring it is so placed up against the lower side of the same that the bar 24 will pass 40 into the cavity of the ring. The cover is then rotated in proper direction to cause the ends of the bar to climb up on the lugs 29, the movement being continued until the bar meets abutments such as the adjacent 45 lugs 30 through which two of the bolts 14 pass. The springs 26 exert a pressure on the bar and hold it firmly on the lugs 29 so that the cover is firmly locked to the 50 ring, yet it is readily removable by rotating it in the opposite direction.

What I claim is:

1. A signal lamp comprising a hollow canopy, a bottom member, a cylindrical lens between the canopy and the bottom member, a plurality of bifurcated lugs radiating from the inner wall of the canopy, the said inner wall adjacent the upper side of the slotted lugs being inclined upwardly and inwardly, an extension at the outer end 55 of each bifurcation which projects toward the said inclined wall but is spaced therefrom, a plurality of bolts adapted to be inserted into the slots of the lugs respectively to cause their heads to engage the top side 60 of the lugs upon opposite sides of the slots

therein, the spacing between the inclined wall of the canopy and the upper ends of each pair of said extensions being such that the head of the bolt will pass through the same only when the bolt is inclined, the said 70 wall also preventing vertical movement of the bolts when they are suspended on the lugs, the said bolts being extended through the interior of the lens and through the base, and means on the bolts to clamp the 75 canopy and the bottom member upon opposite ends of the lens.

2. A signal lamp comprising a hollow canopy, a ring, a cylindrical lens between the canopy and the ring, a plurality of bolts 80 suspended from the inner wall of the canopy for universal movement thereon and extended through the interior of the lens and through the ring, means on the canopy to prevent vertical movement of the bolts, means on the bolt suspending means to prevent inward lateral movement of the top of the bolts, means on the bolts to clamp the canopy and the base upon opposite ends of the lens, a cover for the bottom face of the 85 base and cooperating means on the ring and the cover for releasably locking the cover to the ring.

3. A signal lamp comprising a canopy, a cylindrical lens, a bottom member having a central opening therein, a plurality of bolts releasably suspended from the canopy and extended through the interior of the lens and through the bottom member, nuts on the bolts to clamp the canopy and the bottom member upon opposite ends of the lens, a plurality of cams on the bottom member adjacent the said opening, a cover for the bottom side of the bottom member for covering the said nuts and said opening, a member mounted on the cover for movement toward and from the same, and resilient means tending to retain the said member in contact with the cover, the said member being adapted to engage the cams 100 when the cover is rotated for locking the cover to the bottom member.

4. A signal lamp comprising a hollow canopy, a bottom member, a cylindrical lens between the canopy and the bottom member, a plurality of bifurcated lugs formed on the inner wall of the canopy, a plurality of bolts removably suspended on the lugs respectively and extending within the lens and through the bottom member, means on the lugs to prevent unintentional lateral movement of the heads of the bolts thereon, means adjacent to the heads of the bolts to oppose upward longitudinal movement of the bolts and means on the bolts to clamp 115 the canopy and bottom member upon the lens.

5. A signal lamp comprising a canopy, a lens, a bottom member having a central opening therein, means carried by the can- 120

opy and engaged to the bottom member for securing the canopy and the bottom member on the lens, a plurality of cams on the bottom member adjacent the said opening, 5 a cover for the bottom side of the bottom member, a member mounted on the cover for movement toward and from the same, and means opposing one of said movements

of said member, the said member being adapted to engage the cams when the cover 10 is rotated for locking the cover to the bottom member.

In witness whereof I have hereunto signed my name this 8th day of November, 1924.

ROBERT J. GASKILL.
